CLAIM

The ornamental design for a bookcase façade, as shown and described.

DESCRIPTION

FIG. 1 is a front view in elevation of the bookcase façade of the present invention;

FIG. 2 is a rear view of the panel of FIG. 1;

FIG. 3 is a top plan view;

FIG. 4 is a bottom plan view; and,

FIG. 5 is a side view of the panel of FIG. 1, the opposite side being identical.

The broken lines are for environmental purposes only and form no part of the claimed design.
